DOOR AND GATE FASTENER

Filed July 7, 1924

2 Sheets-Sheet 2

UNITED STATES PATENT OFFICE.

WILLIE J. FAIRBANK, OF SOLDIER, KANSAS.

DOOR AND GATE FASTENER.

Application filed July 7, 1924. Serial No. 724,676.

To all whom it may concern:

Be it known that I, WILLIE J. FAIRBANK, a citizen of the United States, residing at Soldier, in the county of Jackson and State 5 of Kansas, have invented certain new and useful Improvements in Door and Gate Fasteners; and I do declare the following to be a full, clear, and exact description of the invention, such as will enable others skilled 10 in the art to which it appertains to make and use the same.

My invention relates to improvements in locks and latches for numerous purposes and has reference more particularly to a latch 15 which is designed primarily for use upon swinging or sliding doors and gates, the principal object being to provide an extremely simple and inexpensive, yet a highly advantageous device of this character which 20 may be used in a number of ways, that is, for doors which move either toward the right or the left when closing, whether they are of the swinging or sliding type.

In carrying out the preferred form of 25 construction, a latch lever is provided co-operable with a keeper, said lever being mounted at the inner side of the closure and being operable by means of a rock shaft and handle from the outside of said closure.

Further objects of the invention are to provide a novel arrangement of parts whereby 30 a single spring will move the latch lever to operative position, whether it is movable in one direction or the other when releasing, according to whether the door is of the right 35 or left hand type; to provide a unique form of keeper for co-action with the latch lever; to provide a single staple for securing the operating handle on the rock shaft and for 40 preventing withdrawal of this shaft from adjacent parts of the device; and to provide a novel holding arm for the latch lever which will prevent it from being released when desired.

With the foregoing in view, the invention 45 resides in the novel subject matter herein-after described and claimed, the description being supplemented by the accompanying drawings.

Figure 1 is a perspective view showing the latch applied to the upper section of a hinged barn door.

Figure 2 is a horizontal sectional view.

Figures 3 and 4 are vertical sectional views on lines 3—3 and 4—4 of Fig. 2. 55

Figures 5 and 6 are disassembled perspective views.

Figure 7 is an elevation showing the manner of applying the invention to a sliding door. 60

Figure 8 is a detail side elevation showing a slightly different form of construction.

The drawings above briefly described, illustrate the preferred form of construction and this construction is hereinafter specifically explained, with the understanding however that within the scope of the invention as claimed, numerous modifications may be made.

The numeral 1 designates a flat vertically elongated base plate having a circular opening 2 between its ends and provided on one vertical edge with a laterally bent flange 1^a having two openings 4, leaving an abutment 5 at the central portion of the flange, for a purpose to appear. A second plate 3 is spaced laterally from the plate 1 and has its end portions bent horizontally toward said plate as indicated at 3^a and then bent vertically to provide flanges 3^b which are secured to the upper and lower end portions of the plate 1 by rivets 6. These flanges and the plate 1 are formed with openings 7 for attaching bolts 8 which are adapted to pass entirely through the closure 9, to which the device is secured. The outer ends of the bolts 8 pass through a face plate 10 and secure it against the outer side of the closure, said face plate having an opening 11 alined with the opening 2 and also alined with another opening 12 in the plate 3. The plates 1 and 3 co-operate in forming a casing having two open ends, at one of which the flange 1^a is located, said flange having a horizontal width less than the corresponding width of said casing. 75

A horizontal latch lever 13 passes through the casing above described, between the free edge of the flange 1^a and the plate 3, said lever having a hub 14 whose ends are rotatably received in the openings 2 and 12. Opposite ends of the lever 13 are provided with laterally extending fingers 15 and 16, respectively, and between its ends, said lever is provided with a lateral lug 17 which is 105 disposed at the inner side of the abutment 5.

A wire spring 18 is coiled around the hub 14 between the lever 13 and the plate 1 and the ends of this spring are extended to provide arms 19 which straddle both the lug 5 17 and the abutment 5, the free ends of said arms being passed through the openings 4 and bent inwardly toward each other as indicated at 20. By this construction and arrangement of parts, regardless of the direction 10 in which the lever 13 must be swung to release it, one of the arms 19 will act against the lug 17 and the other arm will react against the abutment 5, so that the spring will return the lever to its initial position, 15 as soon as it is released.

A novel form of keeper is provided for co-operation with the latch lever 13, whether it be used in connection with a hinged or a sliding door. In constructing 20 this keeper, I use a vertically elongated metal plate 22, bend its ends laterally as indicated at 23 and then bend them vertically to provide attaching flanges 24. The intermediate portion of the plate 22 is formed 25 with a vertically elongated slot 25 whose central portion opens through one vertical edge of the plate as indicated at 26. The metal above and below the lateral or throat portion 26 of the slot 25 is bent laterally on 30 inclined lines, in the same direction as the bends 23, providing a pair of inclined flanges 27 for engagement with one edge or the other of the lever 13; when the invention is used on hinged doors, and also engageable 35 with one side or the other of the finger 15, when the device is used on sliding doors, as indicated in Fig. 7.

In order that the closure may be held in open position, I provide a suitable hook 28 adapted to be stationarily secured adjacent 40 said closure, to coact with a suitable portion of the latch lever 13, and in order that this lever may be held against release, when the door is closed, I make use of a holding arm 45 29 pivoted at 30 to the closure and provided at its upper end with an angular notch 31 to receive the finger 16, when said arm is swung to the position shown in Fig. 1.

For operating the lever 13 from the outside 50 of the closure, I provide a flat-sided rock shaft 32 which passes through the hub 14 and has engagement with flat internal sides of the latter. This rock shaft passes through the opening 11 of the plate 10 and 55 through a flat-sided opening 33 in a handle hub 34 at the outer side of said plate 10, said hub having oppositely extending operating arms 35 whose free ends are provided with lateral fingers 36. In the angle between one 60 of the arms 35 and its finger 36, a web 37 is preferably formed, said web having an opening 38 through which the shackle of a padlock may be passed to secure the handle to an appropriate staple 39 driven in the frame 65 of a door or some other adjacent fixed sup-

port, so that the closure may be locked from the outside of a building.

To secure the hub 34 upon the shaft 32, and hold said hub against the plate 10, and to prevent withdrawal of the shaft from the latch mechanism and the plate 10, I provide a sheet metal staple 40 which extends longitudinally of the shaft 32, straddles the outer end portion of the latter, and binds frictionally against the opposed walls of the opening 33. The free ends of this staple pass inwardly through the opening 11 and are laterally bent at 41 against the inner side of the plate 10. By placing the staple over the outer end of the shaft 31 and then driving the hub 34 onto the shaft over said staple, the hub is secured upon the shaft with extreme rigidity. The ends of the staple may be bent outwardly at the proper time, and in order to limit the driving of the hub on the shaft, the latter is preferably given a slight twist, as indicated at 42, although this shaft need not be necessarily twisted, as will be seen from Fig. 8. In this figure, the staple 40 is shown secured to the shaft by a rivet 40a. This construction may in some instances be followed, if desired.

It will be seen from the foregoing that a simple, inexpensive and compact device has been provided for right and left hand doors, 95 or other closures, whether they be of the sliding or swinging type, and as excellent results have been obtained from the details disclosed, such details are preferably followed. However, as above stated, within 100 the scope of the invention as claimed, modifications may be made.

I claim:—

1. A latch comprising a base, a latch lever pivoted on said base in laterally spaced relation therewith, said latch lever having a lateral lug spaced from its pivot and projecting toward said base and the latter being provided with a lateral abutment extending toward said lever and overlapping said lug, and a spring having two arms straddling said lug and abutment, whereby when the latch lever is swung in either direction, one arm of the spring will act against said lug and the other arm will react against said abutment.

2. A latch comprising an open-ended casing having opposed side plates formed with aligned circular openings, one of said plates having a lateral flange at one end of the casing provided with a pair of spaced openings, a latch lever passing through said casing between the other side plate and the flange and having a hub whose ends are rotatably received in said circular openings, said latch lever also having a lateral lug at the inner side of said flange between the openings thereof, and a coiled spring around the hub between the lever and said one side plate, said spring having its ends

extended to form arms which straddle said lateral lug and pass through the openings of said flange.

3. In combination with a latch operating shaft, a face plate having an opening through which said shaft passes, and an operating handle having a hub at the outer side of the face plate through which one end of said shaft passes; a staple whose arms straddle the shaft and pass longitudinally through the hub to bind it on said shaft, the free ends of said staple arms passing also through the opening of said face plate and being bent laterally to hold the shaft against withdrawal from said opening.

4. An operating handle for a latch-controlling closure-carried shaft, comprising a hub to be mounted on the shaft, a pair of arms projecting oppositely from the outer end of said hub and having inwardly projecting fingers at their outer ends, and a

web in the angle between one arm and its finger, said web having an opening to receive a padlock shackle.

5. A latch keeper comprising a flat vertical plate having its upper and lower ends bent horizontally in the same direction and then bent vertically to provide attaching flanges, the plate being formed with a vertical slot whose intermediate portion opens laterally through one vertical edge of said plate, the metal at the upper and lower ends of the lateral portion of the slot being bent on inclined lines in the same direction as the first bends given to the ends of the plate, providing inclined flanges either of which is operative for guiding a latch member into the slot.

In testimony whereof I have hereunto affixed my signature.

WILLIE J. FAIRBANK.
